METHOD OF SPRAYING MOLTEN PULVERIZED QUARTZ OR ENAMEL MIXTURES

Earl F. Callan, Glendale, Calif.

Application September 27, 1935, Serial No. 42,428

1 Claim. (Cl. 91—70)

My invention relates to method of spraying molten pulverized quartz or enamel mixtures and has for its principal object, to provide a relatively simple and easily practiced method for applying quartz or enamel mixtures to surfaces and various articles and the practice of which improved method, may be accomplished with a material saving of time, labor and consequent expense.

10 My improved method involves the delivery of finely pulverized quartz or enamel mixtures by means of air under pressure, into a chamber where it is melted under the heat developed by the combustion of gases such as oxygen and acetylene and the molten quartz or enamel mixtures being discharged from the melting chamber directly onto the surface or article to be coated.

It has heretofore been the general practice in the art of enameling to dust, dip, spray or slush articles to be enameled and then place same in ovens to be baked or glazed. In the enameling of bath tubs, sinks, sheet iron and the like, the general practice is, to preheat the articles to be enameled and then to spray or dust the enamel powder thereupon and the article afterwards heat treated or baked, to fix the enamel coating.

20 My improved process enables molten quartz or enamel mixtures to be sprayed directly onto various articles such as bath tubs, sinks, sheet metal, kitchen utensils, stoves, refrigerators, automobile parts, signs, wall tile and the like without involving heat treatment or baking of the articles after the glaze or enamel has been applied to the surfaces thereof.

25 Further, my improved process enables the bottoms of vessels to be sprayed with a specially prepared finely pulverized quartz, to form a protective coating that will prevent the development of rust and also prevent barnacles and the like, from attaching themselves to the surfaces.

30 Further, my improved method may be advantageously employed in spraying molten quartz onto wire cloth to provide a sheet or panel that will admit infra-red visible and ultraviolet rays or radiations and these coated sheets may be used to cover sun porches, hospital convalescing wards and the rooms where special light ray treatments are given.

35 In practicing my improved method, I prefer to use a simple form of spray gun, as illustrated in the accompanying drawing wherein

Fig. 1 is a vertical section taken through the center of the spray gun.

40 Fig. 2 is a cross section taken on the line 2—2 of Fig. 1.

Fig. 3 is a cross section taken on the line 3—3 of Fig. 1.

Fig. 4 is a sectional view of a form of spray gun having means for preheating the powdered or pulverized quartz or enamel mixtures before the same enter the melting chamber.

Referring by numerals to the accompanying drawing which illustrates a simple and convenient form of spray gun that may be used in practicing my improved method, 10 designates a handle which may be formed of wood, metal or composition and which is shaped somewhat similar to the handle of a pistol in order that the device may be conveniently held and manipulated.

45 Removably mounted on the upper end of the handle, is a substantially cylindrical housing 11 and projecting from the forward end of said housing, is a short tubular nozzle 12.

50 Disposed within the housing 11 and detachably applied to the handle 10, is a nozzle 13 provided with an axial bore 14 that communicates with a duct 15 that passes lengthwise through the central portion of handle 10.

Connected to the lower end of the handle 10 and communicating with bore 15, is a valve 16 25 and connected thereto is a flexible tube 17 that leads from the pulverized quartz or enamel mixture source of supply.

55 The pulverized material is forced through tube 17 and ducts 14 and 15 by compressed air and the flow of the powdered material may be controlled by proper manipulation of valve 16.

The forward end of nozzle 13 terminates a short distance inwardly from the inner end of nozzle 12 and port 14 is in direct axial alignment with said nozzle 12.

60 Arranged for sliding movement through the intermediate portion of handle 10, is a valve 18 that controls the flow of pulverized material through duct 15 and said valve is normally maintained in closed position by an expansive coil spring 19.

65 A trigger 20 is pivotally mounted on handle 10 with the lower portion of said trigger bearing against the projecting end of valve 18, thus providing means for conveniently opening valve 18 while the spray gun is held in the hand.

70 Formed through handle 10 is a duct 21 and seated in the lower end of the handle and communicating with said duct, is a valve 22.

75 Connected to valve 22 is a flexible tube 23 that leads to a source of acetylene supply.

80 In the upper end of the handle 10, the duct 21 communicates by means of branch ducts 24 with ducts 25 that are formed through nozzle 12 so that

a plurality of jets of acetylene are discharged from the forward end of nozzle 13.

A duct 26 passes lengthwise through handle 10 and seated in the lower end of said handle and communicating with said duct is a valve 27, to which is connected a flexible tube 28 and the latter leading to a suitable source of oxygen supply.

The upper end of duct 26 communicates by means of branch ducts 29 with ducts 30, that are formed through the nozzle 13.

The ducts 25 through which the acetylene gas passes are preferably alternately arranged with the ducts 30 through which the oxygen passes and all of said ducts are disposed about the central duct 14 through which the pulverized quartz or enamel mixtures pass.

In Fig. 4 I have illustrated a spray gun structure having means for preheating the quartz or enamel mixtures before the same enter the melting chamber and in this construction the upper end of duct 15 is connected outside the housing 11 to one end of a tube 15^a that is coiled around the housing 11 and the other end of said tube 25 communicates with duct 14 in the nozzle 13.

In practicing my improved method with the apparatus disclosed pulverized quartz or enamel mixtures pass from the source of supply through flexible tube 17, duct 15 and bore 14, said pulverized material being under air pressure and the volume flow of material to the spray gun, being regulated by means of valve 16.

The flow of the pulverized material through the spray gun is controlled by manual operation of valve 16.

Simultaneous with the discharge of pulverized material from the spray gun, acetylene gas and oxygen or other combustible gases capable of producing relatively high degrees of heat, pass from their sources of supply through tubes 23 and 28, ducts 24 and 26, thence through the branch ducts 24 and 28 and thence through ducts 25 and 30 in nozzle 13.

These gases are ignited at the discharge end of nozzle 13, thereby producing a blow flame having relatively high degrees of heat and as a result, the finely powdered or pulverized quartz or enamel

mixtures discharging from the end of bore 14 are instantly melted and in such condition are forcibly blown through nozzle 12 against the surface that is to be coated.

Due to the fact that the quartz or enamel mixtures are specially prepared and finely pulverized before being delivered to the spray gun, said material will melt instantly as it discharges from the nozzle of the gun and which nozzle also discharges the acetylene and oxygen gases that are ignited within the melting chamber and which pass therefrom outwardly through nozzle 12.

In the construction illustrated in Fig. 4, the pulverized material in passing through the coil 15^a, is effectively preheated before being discharged from the nozzle 13 and such preheating of the material enables lower temperatures to be utilized in melting the pulverized material.

Obviously various types and forms of spray guns other than the one herein shown and described may be advantageously employed for simultaneously melting and spraying pulverized quartz or enamel mixtures onto the surfaces to be coated.

Thus it will be seen that I have provided a relatively simple and easily practiced method of and apparatus for melting pulverized quartz and enamel mixtures and spraying the same directly onto the articles or surfaces to be coated.

I claim as my invention:

The herein described method of spraying molten pulverized coating mixtures which consist in producing a substantially circular blow-flame within a chamber having an outlet opening directly in front of and in alignment with said flame, causing the pulverized coating mixture to flow axially through the circular blow-flame so that it is pre-heated by the heat developed by said blow-flame within said chamber, causing the pre-heated pulverized mixture to flow with the circular blow-flame through the chamber toward the outlet opening, so as to melt said pulverized coating mixture and causing the same in molten condition and said circular flame to discharge through said outlet opening so that the molten mixture is delivered directly onto the surface to be coated.

EARL F. CALLAN.
